UNITED STATES PATENT OFFICE.

WALTER S. HAVEN, OF RACINE, WISCONSIN.

FLOOR-DRESSING MACHINE.

No. 902,398.

Specification of Letters Patent.

Patented Oct. 27, 1908.

Application filed April 25, 1907. Serial No. 370,270.

To all whom it may concern:

Be it known that I, WALTER S. HAVEN, doctor of medicine, a citizen of the United States, residing at Racine, county of Racine, 5 State of Wisconsin, have invented certain new and useful Improvements in Floor-Dressing Machines; and I do hereby declare the following to be a full, clear, and exact description of the invention, such as will enable 10 others skilled in the art to which it appertains to make and use the same.

This invention relates to certain improvements in floor dressing, surfacing or polishing machines; and the objects and nature of my 15 invention will be readily understood by those skilled in the art in the light of the following explanation of the construction shown in the accompanying drawings to illustrate what I now consider the preferred embodiment of 20 my invention from among other variations and arrangements within the scope of the following claims.

The invention consists in certain novel features in construction and in arrangements 25 and combinations of parts as more fully and particularly set forth hereinafter.

Referring to the accompanying drawings:—Figure 1, is a perspective view of one form of my floor dressing machine. Fig. 2, 30 is a longitudinal vertical section through a floor surfacing machine showing the structure of Fig. 1, with the exception that the floor engaging tool is arranged on the same side of the fulcrum as the lever instead of on the opposite side as in Fig. 1. Fig. 3, is a a cross sectional view of the structure of Fig. 1. Fig. 4, is a perspective view of a modification. Fig. 5, is a detail perspective of a portion of the movable carrier, the loose ful- 35 crum sleeve thereon, and a form of scraper tool carried by the sleeve. Fig. 6, is a detail perspective of a modification. Fig. 7, is a detail perspective showing a polishing or finishing pad which can be removably applied to 40 the hand lever instead of the scraper shown by certain other views of the drawings.

The machine shown comprises means for maintaining one or more tracks or runways above and approximately parallel with the 45 floor to be dressed, a carrier movable along said tracks, and a hand lever mounted or fulcrumed on or to said carrier and provided with a floor surfacing tool of any suitable or desirable nature or construction, whereby the 50 operator through the medium of the lever, reciprocates the tool and applies the same to

the floor with the desired pressure. The track or tracks form the backing, support or means which enables the operator to attain the lever action on the tool in pressing the 60 same to the floor. The track or tracks is or are essential to the broad feature of my invention, whereby the leverage of the tool against the floor is attained, but the means for fixing the tracks relates to the specific features of 65 my invention.

If preferred, the tracks might form a part of a frame work so arranged that the means employed to fix or maintain the tracks would consist of a part of the frame on which the 70 operator could stand so that his weight would hold the tracks in place. Under this specific arrangement, my invention comprises a horizontally disposed frame provided with a fixed or movable platform adapt- 75 ed to rest on the floor to be dressed and designed to be manually shifted along or over any desired portion of the floor as the work of dressing the surface thereon progresses. A suitable track or runway is attached to and 80 projects from this frame or constitutes a part thereof, and this track is arranged parallel with and a suitable distance above the floor surface to be dressed. A reciprocating carrier is confined to the track and carries a 85 floor dressing tool or element and a hand lever whereby the carrier and tool can be recipro- 90 cated and whereby the tool is held to the floor surface with the desired amount of pressure. The operator usually stands on the platform so that his weight will hold the machine in position on the floor and against slipping or sliding during the dressing operation, although other means might be provided for this purpose. The hand lever usu- 95 ally extends upwardly and rearwardly so as to be readily accessible to the operator as he stands behind the machine or on the platform thereof, whereby the lever can be em- 100 ployed as a handle to reciprocate the carrier provided with the floor dressing element and at the same time as a lever to hold said ele- 105 ment down to its work.

In the specific examples illustrated in the drawings, I provide a strong rectangular or 105 oblong open frame work constructed of any suitable material, and at one end carrying the frame or platform 1, on which the operator can stand. This platform can be of any suitable or desirable construction and of a 110 size to receive one or both feet of the operator. I usually mount the frame on any suit-

able legs or other floor supports 2, adapted to rest on the floor and hold the frame in a horizontal position and elevated from the surface of the floor although I do not wish to so limit my invention. If so desired certain or all of these supports 2, can be provided with friction or biting surfaces 20, to engage the surface of the floor and aid in holding the machine in position on the floor and against slipping during the reciprocation of the dressing tool.

In the specific examples illustrated, the spaced parallel side bars 3, of the frame form tracks or runways, and are rigidly spaced 15 and secured together by the frame ends or cross bars 4, with the end legs 2, depending from the frame corners.

The platform 1, is shown arranged across an end of the frame and mounted on the side 20 bars thereof. I show the platform mounted on the frame bars so as to be capable of being moved longitudinally thereof in case it is desired to shift the position thereof for any reason, but do not wish to so limit my invention. I show each frame side composed 25 of a pair of spaced parallel bars 3, arranged one over the other and forming a longitudinal slide or runway, although I do not wish to so limit my invention.

30 In the specific example illustrated, a reciprocating carrier 5, is arranged transversely of the frame between and confined to the sides thereof to reciprocate longitudinally thereof. The carrier shown consists of a 35 strong cross bar 5, at its ends confined to said slideways by any suitable means. For instance, in Fig. 4, I show the bar 5, fixed to slides 6, confined to slide between or on the frame bars 3, while in Figs. 1, 2, and 3, I 40 show the bar 5, carried by and forming the axle of grooved rollers 7, confined between the double frame sides to travel longitudinally thereof. A hand lever 8, is supported by said carrier which forms the lever fulcrum. The lever extends upwardly from 45 the carrier and toward the end of the frame provided with the platform. The portion of the lever depending from the carrier is provided with any suitable floor polishing, finishing or surfacing tool.

50 I usually form or provide the lever with a sleeve 9, mounted on the carrier 5, and in all of the constructions shown, except the construction of Fig. 4, this sleeve is free to slide longitudinally of and turn or oscillate axially on the carrier 5. This sleeve 9, couples the lever to the carrier and enables the lever to rock vertically on the carrier as a fulcrum or center.

60 The inclined lower arm of the lever is usually formed by a socket 10, rigid with and projecting downwardly and radially from the sleeve 9 at an inclination to the floor, in connection with the shank 11, of the floor 65 gaging tool fitted removably in the socket

and secured by any suitable means such as set or clamping screw 12, so that the tool can be removed for repair or sharpening or to permit application of another tool of a different form or character.

In Figs. 1, 2, 3 and 5, I show scrapers of various forms consisting of inclined flat blades 13, secured to shanks 11, removably fitted and secured in the sockets 10, of the lever fulcrum sleeves or sockets 9.

In Fig. 6, I show the fulcrum sleeve 9, of the lever formed with a rigid depending lug or arm 14, to which shank 15 of scraper blade 13, is removably clamped by U-shaped bolts 16.

In Fig. 7, I show a smoothing, surfacing, 80 polishing or rubbing pad consisting of head 17, having the bottom rubbing surface 18, of any suitable polishing or abrading material. This pad is removably secured to the lever by a shank 19, clamped in socket 10. The shank being pivotally joined to head 17, by suitable means, such as eyes 20.

In Fig. 4, the lever sleeve 9, preferably oscillates on the carrier 5, but is held against longitudinal movement.

The socket 10, of the lever is shown removably receiving the shank of a forked head 21, forming the lower end of the lever and carrying a floor surfacing or polishing tool in the form of an elongated horizontal rotating 95 wheel or cylinder 22. Any suitable means can be provided for rotating said cylinder as the carrier is reciprocated by the lever, and by rocking the lever, the cylinder can be held to or raised from the floor.

100 As a means which might be employed to positively rotate the cylinder, I show a toothed rack 23, secured longitudinally to one of the frame bars 3. One end of the bar 5, carries a loose pinion 24, in mesh with the rack, and this pinion 24, is fixed to a large gear 25, meshing with a pinion 26, fixed on the end of cylinder 22.

In Fig. 2, I show the lower end of the lever extended rearwardly, so that downward pressure on the handle end of the lever, moves the tool to the floor, whereas in the other figures I show the lower end of the lever extended forwardly so that the tool is held to the floor by upward pressure on the handle 115 end of the lever.

120 In all the structures shown, except that of Fig. 4, the lever is movable laterally, by the sleeve 9, sliding longitudinally of bar 5, so that the tool can operate over an extended area of floor, before it becomes necessary to shift the position of the frame to bring a fresh area of floor within the range of action of the tool.

125 If so desired the lever 8 can be formed, as shown by Fig. 6, with two upwardly diverging handle ends 8, so that two operators facing each other can actuate the device.

I do not wish to limit myself to the means shown for maintaining the reciprocatory 130

carrier to reciprocation over the floor surface and to hold said carrier down to sustain the pressure of the lever when holding the tool to the floor surface, as various forms and arrangements of track or guide way devices might be employed for this purpose, nor do I wish to limit all features of my invention to the employment of the tool controlling lever as the manual means for reciprocating the carrier.

It is evident that various changes and modifications might be resorted to, that parts might be omitted and other parts added, without departing from the spirit and scope of my invention, and hence I do not wish to limit myself to the exact constructions disclosed.

Having thus described my invention, what I claim is:—

20 1. A portable manually operated floor dressing machine comprising a runway, a reciprocating carrier confined thereto, an actuating lever carried by and fulcrumed on said carrier, and a floor dressing tool carried by said lever and raised to and from the floor surface thereby.

25 2. A portable manually operated floor dressing machine comprising a frame adapted to rest on the floor and forming a slide-way over the floor surface, and a reciprocating vertically swingable tool carrying lever carried by and provided with a fulcrum movable along said slide-way.

30 3. A portable manually operated floor dressing machine comprising a frame adapted to rest on and be shifted along the floor to be dressed and provided with a slideway and a reciprocating carrier confined to said slide-way and provided with a manually controlled operating lever swinging thereon and provided with a floor dressing tool.

35 4. A floor dressing machine comprising a frame, and a vertically movable manually operated lever at the lower free end adapted to receive a floor dressing tool, and provided with a movable fulcrum adapted to reciprocate along said frame.

40 5. A floor dressing machine comprising a frame adapted to rest on and be shifted along the floor to be dressed, a carrier adapted to reciprocate along said frame, and a manually operated lever carried by and fulcrumed on said carrier to rock vertically and adapted to carry and control a floor dressing tool.

45 55 6. A portable manually operated floor dressing machine comprising a frame adapted to rest on the floor and to be moved along the same as the work progresses and forming a track above and parallel with the floor, and a vertically rockable hand lever adapted to receive and control the floor dressing tool and provided with a fulcrum adapted to reciprocate longitudinally of said track.

60 65 7. A portable manually operated floor dressing machine comprising a frame adapt-

ed to rest on the floor to be dressed, and a vertically rockable longitudinally and laterally movable hand lever confined to said frame to reciprocate longitudinally thereof and adapted to receive, carry and control a floor dressing tool.

8. A portable manually operated floor dressing tool comprising a frame, and a vertically rockable hand lever confined to said frame and provided with a sliding fulcrum to reciprocate longitudinally of the frame, said lever provided with and controlling a floor dressing tool.

9. A portable manually operated floor dressing machine comprising a frame adapted to rest on the floor to be dressed, and a reciprocating carrier adapted to support a floor dressing tool and provided with a manually operated vertically swinging lever fulcrumed thereto for reciprocating the carrier and pressing the tool to the floor surface.

10. A portable floor dressing machine comprising a frame adapted to rest on and be shifted along the floor and embodying a platform to support the operator and a longitudinal track and a vertically swinging lever adapted to receive and control a floor dressing tool and provided with and fulcrumed to a supporting carrier movable along said track.

15 95 11. A portable floor dressing machine comprising a frame adapted to rest on the floor and embodying a platform to support the operator, and a reciprocating floor dressing tool carrier confined to the frame and provided with an operating and controlling hand lever fulcrumed thereto, and accessible to the operator on the platform.

12. A portable floor dressing machine comprising a frame embodying a platform adapted to receive the operator and a pair of tracks connected to the platform and extending therefrom along the floor, a reciprocatory carrier extending between and confined to said tracks, and a vertically rocking hand lever fulcrumed on said carrier and movable longitudinally of said carrier and at its lower end adapted to receive a floor dressing tool.

17 110 115 13. A portable hand operated floor dressing machine comprising a track, a carrier supported by and held to reciprocate in a fixed plane by the track, and a vertically swinging hand lever fulcrumed to the carrier and whereby the carrier is reciprocated; and a floor dressing tool carried by the lower end of the lever.

14. A portable hand operated floor dressing machine comprising an elongated track provided with means whereby the same is held fixed above and parallel with the floor during operation, and a hand lever having a fulcrum confined to reciprocate along said track, said lever adapted to receive a floor dressing tool.

15. A portable hand operated floor dress-

- ing machine comprising a track provided with means, whereby, during operation, the track is fixed above and parallel with the floor by a weight, and a floor dressing tool 5 carrying and applying hand lever having a fulcrum confined to and movable along said track.
16. A floor dressing machine comprising a reciprocatory carrier having a horizontally 10 elongated fulcrum, and a carrier-actuating and tool-carrying and controlling hand lever mounted on said fulcrum to rock vertically, said lever being laterally movable along said fulcrum for the purposes, substantially as set 15 forth.
17. A floor dressing machine comprising a carrier adapted to reciprocate over the surface of the floor to be dressed, and a tool-carrying lever fulcrumed to said carrier to 20 rock vertically and mounted on the carrier to shift laterally and independently of the carrier, substantially as described.
18. A floor dressing machine comprising a reciprocatory carrier, means holding the 25 same to reciprocation parallel with the surface to be dressed, a tool-carrying and controlling hand lever mounted on said carrier to move laterally thereof to carry the tool to work in different vertical planes without 30 shifting the position of the carrier laterally.
19. A floor-scraper comprising a truck having a beam adjustable longitudinally of the truck-axle, and a blade-head in connection with the beam.
- 35 20. A floor dressing machine comprising a movable carrier, and vertically rockable means movable transversely of said carrier and carried thereby and provided with a floor dressing tool head.
- 40 21. A floor dressing machine comprising a reciprocating carrier, means confining said carrier to reciprocation in a certain plane, a floor-dressing-tool support movable with said carrier and independently movable 45 transversely thereof, and means for shifting said support transversely of said carrier.
22. A floor dressing machine comprising a reciprocating carrier having a slide-way arranged transversely thereof, a vertically 50 rockable support provided with a tool head and mounted on said way to move freely
- thereon transversely of the direction of working reciprocation of said carrier, and actuating and controlling means for said support whereby the same can be rocked vertically to move said head to and from operative position, and whereby said support can be freely moved longitudinally along said way to vary the working position of said head. 55
23. A floor dressing machine comprising a movable carrier, and a vertically rockable lever freely movable transversely of the carrier and provided with a tool head. 60
24. A floor dressing machine comprising a movable carrier, a lever movable transversely of said carrier, and a vertically movable tool head movable transversely with said lever. 65
25. A floor dressing machine comprising a reciprocatory carrier, a track to confine the carrier to reciprocation in a fixed plane approximately parallel with the floor surface, a movable tool head carried by the carrier, and a handle to reciprocate the carrier and to 70 move the tool head transversely of the direction of the reciprocation of the carrier. 75
26. A floor dressing machine comprising a reciprocatory carrier, a track to confine the carrier down to reciprocation along the surface to be dressed, a handle movable transversely of and mounted on said carrier, and a tool head carried by said handle and adapted to be moved thereby transversely of the direction of the reciprocation of the carrier. 80 85
27. A floor dressing machine comprising a reciprocatory carrier, means to hold the carrier down to reciprocation in a plane approximately parallel to the floor surface to be dressed, a vertically movable tool head carried by the carrier, and a handle for reciprocating the carrier, said handle being movable transversely of the carrier and connected with said tool head for shifting the same transversely of the direction of reciprocation 90 of the carrier. 95
